UNITED STATES PATENT OFFICE.

WILLIAM E. WOODARD, OF FOREST HILLS, NEW YORK.

RAILWAY TRUCK.

1,417,653.

Specification of Letters Patent. Patented May 30, 1922.

Application filed July 13, 1920. Serial No. 395,907.

To all whom it may concern:

Be it known that I, WILLIAM E. WOODARD, a citizen of the United States, residing at Forest Hills, in the county of Queens and State of New York, have invented certain new and useful Improvements in Railway Trucks, of which the following is a specification.

This invention relates to railway trucks, particularly to trucks of the "swing" or "lateral motion" type, and while it is more especially useful in connection with locomotive engine trucks, it may be adapted to service in trucks for tenders and other railway vehicles. It is particularly adaptable for use in connection with narrow gauge locomotives and locomotives in which the swing of the bolster is very large.

More specifically considered, my invention has to do with trucks of the inverted rocker type, and one of its primary objects is the provision of an improved connection between the bolster and the rocker which is simple and effective and does not have certain objections inherent in previous trucks of this general character, and which insures proper register between the bolster and the rocker at all times. Another object of the invention resides in the provision of a connection of the character specified by means of which the rocker will properly follow the bolster in the event of the lifting of the bolster in and out of the truck.

These and such other objects as may hereinafter appear, or are incident to my invention, I obtain by means of a construction which I have illustrated in preferred form in the accompanying drawings, wherein:

Fig. 1 is an end elevation and partial transverse section through a two-wheel truck to which my improvements have been applied; Fig. 2 is a plan view of the truck shown in Fig. 1; Fig. 3 is a section taken on the line 3—3 of Fig. 1; Figs. 4, 5 and 6 are respectively a side elevation, an end elevation and plan view of the rocker employed in carrying out my invention; Fig. 7 is a perspective view of a member forming part of the connection between the truck, bolster and rocker; and Fig. 8 is a bottom plan view of the device shown in Fig. 7.

In the drawings I have shown my improvements as applied to a two-wheel truck but it will, of course, be understood that it is applicable to other types of trucks. Referring now to the drawings, the truck A is a standard form of truck commonly used in railroad service and it includes a main frame 1, preferably of cast steel, which carries the wheels 2, axle 3 and bearing boxes 4 in the customary manner. The truck bolster is indicated at B and it is provided with the customary center pin 5, slotted at 6 to receive an end of the equalizing bar 7, and it is provided on its lower face with the V-shaped bearing members 8^a which are adapted to rest upon the rocker indicated at C. The rocker C comprises the cams 8, each of which, at the bottom, at opposite edges, is provided with a journal 8^a; the intermediate portion 9, which serves to connect the two cams and is preferably formed integrally therewith; and the upstanding lugs 10, preferably formed integrally with the portion 9. These lugs 10 are spaced and at their upper ends are provided with a pin or connecting member 11, the purpose of which will appear.

Depending from the bolster B is a member 12 provided with a head 13, such member being forked at the bottom so as to fit over the pin 11 in the manner shown in Fig. 1 and Fig. 3. The forked ends of the member 12 are apertured for the reception of the bolt or pin 14, the parts being so disposed that there is considerable lost motion between pins 11 and 14. Where the depending member 12 is not made integral with the bolster, but is a separate member, as shown, the head 13, thereof is slotted, as at 15, so as to receive the end of the equalizing bar 7 which thus serves to hold the member in place.

The connection thus formed between the bolster and the rocker is a simple and effective one, takes up a minimum space, and always insures proper register of the bolster and rocker, the advantages of which will be readily understood by those skilled in the art. Furthermore, there is sufficient lost motion for all normal conditions and in the event of the lifting of the bolster in and out of the truck the rocker properly follows the bolster, a feature which has many practical

advantages. It will be clear that the improvements are particularly useful in narrow gauge trucks and where the swing of the bolster is very large, and they are applicable to trucks having more than one rocker.

What I claim is:

1. A lateral motion truck comprising in combination with the truck frame, a bolster, 10 an inverted rocker between the frame and the bolster, and means providing a lost motion connection between the bolster and the rocker.
2. In a railway truck, the combination of 15 a bolster, an inverted rocker, and means for securing register of the bolster and rocker depending from the bolster and adapted to engage the rocker.
3. In a railway truck, the combination of 20 a bolster, an inverted rocker, a projection on the rocker, and means depending from the bolster and adapted to engage said projection for securing registry of the bolster.
4. In a railway truck, the combination of 25 a bolster, an inverted rocker on which the bolster rests, and a substantially vertically extending member connecting the bolster and rocker.
5. In a railway truck, the combination of 30 a frame, a bolster, an inverted rocker intermediate the frame and bolster on which the bolster rests, and a substantially vertically extending member forming a lost

motion connection between the bolster and the rocker.

6. In a railway truck, the combination of a frame, an apertured bolster, an inverted rocker intermediate the frame and bolster on which the bolster rests and a headed connecting member on the bolster the shank of 40 which depends through said aperture.

7. In a railway truck the combination of an apertured bolster, a rocker, an equalizing bar, and a headed connecting member the shank of which depends through said aperture, the equalizing bar being adapted to rest on the head of said member.

8. A lateral motion truck comprising in combination with the truck frame, a bolster, 50 an inverted rocker between the frame and the bolster, and means for securing register of the bolster and the rocker comprising means depending from the bolster and means on the rocker engaged thereby.

9. A lateral motion truck comprising in 55 combination with the truck frame, a bolster, an inverted rocker resting on the frame and adapted to support the bolster, and a lost motion connection between the bolster and the rocker which is adapted to carry the 60 rocker with the bolster upon occasions when the latter is lifted from the truck.

In testimony whereof, I have hereunto signed my name.

WILLIAM E. WOODARD.
